(57) **CLAIM**

We claim the ornamental design for a dough-holding campfire cooking utensil distal end portion, as shown and described.

DESCRIPTION

FIG. 1 of the drawings is a perspective view showing the proximal back side and top side of a dough-holding campfire cooking utensil distal end portion embodying the design of my invention;

FIG. 2 is a perspective view showing the distal front side and bottom side of said distal end portion;

FIG. 3 is a right side elevation view;

FIG. 4 is a top plan view;

FIG. 5 is a left side elevation view;

FIG. 6 is a bottom plan view; and,

FIG. 7 is a reduced-in-scale perspective view showing the proximal back side and top side of the distal end portion in its usual environment, connected to a rod-and-handle component illustrated in broken lines.

The portions shown in broken lines in FIG. 7 are for illustrative purposes only and form no part of the claimed design.
